DISPENSING CONTAINER FOR MEDICAMENTS OR THE LIKE

Lloyd S. Turner, Los Gatos, and Daniel G. Vaughan, Monte Sereno, Calif., assignors to Barnes-Hind Diagnostics, Inc., Carolina, Puerto Rico

Filed Mar. 1, 1973, Ser. No. 337,102

Term of patent 14 years

Int. Cl. D9—01
U.S. Cl. D9—2

FIG. 1 is a perspective view of a dispensing container for medicaments or the like showing our new design;

FIG. 2 is an end elevational view;

FIG. 3 is a sectional view taken on the line 3—3 of FIG. 2;

FIG. 4 is a top plan view; and

FIG. 5 is a bottom plan view thereof.

We claim:

The ornamental design for a dispensing container for medicaments or the like, as shown.
